J. D. FARMER

SHOE HEEL

Filed March 15, 1920

FIG. 1.

FIG. 2.

FIG. 3.

Inventor:
James D. Farmer.
By L. G. Fletcher, ally.

UNITED STATES PATENT OFFICE.

JAMES D. FARMER, OF ST. LOUIS, MISSOURI, ASSIGNOR OF ONE-HALF TO LAMARTINE BROOKS FAY AND ONE-HALF TO RALPH G. THOMAS, OF AKRON, OHIO.

SHOE HEEL.

Application filed March 15, 1920. Serial No. 365,806.

To all whom it may concern:

Be it known that I, JAMES D. FARMER, a citizen of the United States of America, and a resident of the city of St. Louis, and State 5 of Missouri, have invented certain new and useful Improvements in a Shoe Heel, of which the following is a specification.

The primary object of this invention is to provide an improvement in shoe heels that 10 are constructed of metal or other analogous material.

Another object of this invention is to provide a shoe heel with improved means for securing it to the sole of the shoe.

15 A further object is in providing improved means for securing the wearing surface of lift to a metallic shoe heel.

Other and further objects will appear in the specification and be specifically pointed 20 out in the appended claims, reference being had to the accompanying drawings exemplifying the invention, and in which,

Figure 1 is a transverse vertical section taken through a shoe heel showing the improvements contained in this invention applied thereto.

Figure 2 is a plan view of the shoe heel.

Figure 3 is an enlarged transverse vertical section of a portion of Fig. 2, and taken 30 on the line III—III thereof.

Referring to the drawings, 1 designates a body portion of which the shoe heel is comprised, said body portion being of a shell like formation, and having a hollowed out portion 2, and formed on said portion 1 is a lower end portion 3, having a recess 4 which is open from the lower end, and formed around said recess at its lower end is an overlapping flange 5, said recess 4 being for the reception of a filling element 6, such as leather or other fibrous material, said filling element providing a securing agent for fastenings such as 7 when they are driven through the wearing surface or lift 8.

45 A dividing wall 9 is provided in the body portion 1 between the hollowed out portion 2 and the recess 4 thereof, and formed in said wall is an opening 10 which is for the reception of a bolt 11, having a head 12, and a threaded end 13, said head being seated in the lift 8, the depression formed by said head 12 in the lift 8 being filled by a compound such as 14.

Formed in the hollowed out portion 2 of 55 the body portion 1 is a plurality of bosses

15, each being for the purpose of securing a heel fastening 16. These fastenings 16 are peculiarly secured in their respective bosses so that they can be removed in the event that they become broken; each fastening being in the form of a nail having a head 17, each nail being inverted so that the head thereof will rest in a bushing 18 which is embedded in the material from which the heel is casted, each of said bushings being 60 threaded interiorly as designated at 19 and are for the reception of respective threaded washers 20 in which each washer is mounted over a respective inverted nail and clamped against the head thereof, thereby holding 65 said nails or fastenings in perpendicular position.

In mounting an improved shoe heel of this character to a shoe, the bolt 11 after being passed through the lift 8 and filling 75 element 6 is passed through an opening provided in the shoe sole 21, where a nut 22 is engaged over the threaded end 13 thereof, said nut clamping on top of the sole 21. The sole is then pressed down until the fastenings 16 have been penetrated through the sole and the ends 23 thereof are clinched or bent as shown in Fig. 1.

For preventing the lift 8 from turning on the bolt 11, pins such as 24, which are 80 carried by the lower end portion 3 are provided.

From the aforesaid description as pertaining to Figs. 1, 2 and 3, it is to be noted that a heel of this improved character can 85 be readily secured to a shoe, and when occasion arises, can be readily removed therefrom by removing the bolt 11 and straightening the fastenings 16, and as already related, in the event that one of these fastenings breaks, the washer 20 can be readily removed, thereby removing the broken fastening and remounting a new fastening.

What I claim is:

1. A shoe heel provided with a plurality of seating means, each having a portion for underengagement with the body of the heel, a penetrating member to be sustained by each respective seating means, and a removable means in each of said seating means for holding each respective penetrating member in operative position.

2. In a shoe heel, a seating means borne thereby having a portion for underengaging a portion of the body of the heel, a pene-

- trating member located in said seating means, and a removable bushing mounted in said seating means for holding the penetrating member in operative position.
5. In combination, a heel, a series of nails projecting upwardly therefrom for attaching the heel to a shoe, each nail having independent individual replaceable means connecting it with the heel.
10. 4. A shoe heel having a metallic body por-
- tion with nails for attaching the heel to a shoe, and set screws embracing the nails.
5. The combination, with a heel having a threaded opening therein, of a nail adapted to rest within said opening, a set screw having a tubular passage therein and adapted to engage the said threaded portion and to abut the head of the nail, whereby the nail may be removably secured to the said heel.

15
JAMES D. FARMER.
